E. P. Clark,
Clothes Drier.

No. 92797.

Patented July 20, 1869.

United States Patent Office.

EDWARD P. CLARK, OF MILLBURY, MASSACHUSETTS.

Letters Patent No. 92,797, dated July 20, 1869.

IMPROVEMENT IN "CLOTHES-DRIER."

The Schedule referred to in these Letters Patent and making part of the same.

To all whom it may concern:

Be it known that I, EDWARD P. CLARK, of Millbury, in the county of Worcester, and State of Massachusetts, have invented certain new and useful Improvements in "Clothes-Driers" or Towel-Racks, of which the following is a full, clear, and exact description, reference being had to the accompanying drawings, making part of this specification, in which—

Figure 1 represents a front elevation, with the sockets B of four of the arms shown in section.

Figure 2 is a top view of fig. 1, and

Figure 3, a modification of the same.

Figure 4 represents the under side of one of the sockets detached, and

Figure 5, a section of a corrugated and perforated arm or bar, E.

This invention relates to that kind of clothes-driers which are secured to the wall or side of a room, where drying-currents of air will circulate around and among the articles hung upon the bars or arms, to carry off the moisture.

This invention has for its object economy, convenience, facility, and durability, and its principal novelty consists in the tapering spindles, the sockets, with tapering holes to fit the spindles, the method of connecting the arms with such sockets, and the means for securing the stand or plate to the wall or side of the room, or to any other suitable support.

The stand or plate, A, has a long slot, h, in its top end, and a shorter slot or nick, g, in its lower end, and above this lower slot a plate, C, or ears project at a right angle from the stand.

Tapering spindles, D, rise from the upper side of each of the ears, or from the plate C, to any convenient height, and on these spindles I place the sockets B, which connect and support the arms or bars E.

The holes a in the sockets are tapering, and the tapering spindles fill the holes, and this insures a fit between the former and the latter, and provides for setting and retaining the arms in any position of their horizontal swing, and keeps them in a horizontal position, whether the spindles and the tapering-holed sockets are new and unworn, or partly or much worn by use, as each tapering spindle and its tapering-holed socket will wear uniformly, and on the same taper.

After moving on arm, E, to the position desired, a pressure on the top of the socket at e, at the same time working the arm slightly, will set the socket to the tapering spindle sufficient to retain the arm in a set position. Said arm may be easily set in any other position, by simply pulling or pushing it round.

It is evident that the tapering spindles and sockets, as described, will endure much longer than straight

spindles, or a straight-holed socket thereon, and will prevent the arms sagging, so common in driers or racks with swinging arms.

Two or more sockets and their arms may be applied to one of the tapering spindles, as shown in section in fig. 1, one arm and a socket below another, but each of the sockets must have a tapering hole, and each successive lower one larger than the next above. By this means, from twenty to fifty or more swinging arms or bars may be employed in a limited space, and such arms perforated, as shown at E', in fig. 2, and the drying-air allowed to pass through the perforations 4, and to the fold or portion of the clothes hung on such perforated arm, thus drying that portion of the clothes as fast, or nearly as fast as the portions which hang vertical, and measurably preventing the wooden arms becoming saturated with water.

The arms may be corrugated as well as perforated, as shown in fig. 5, or the perforations 4 may be omitted, and only corrugations formed. Either or both are effectual and practical.

Either of both edges of the arms may be bevelled, and narrowest at the bottom, so as to allow air to circulate between the cloth F and the edge of the arm, the former coming in contact with the latter only on the tops of the projections e, shown in fig. 5. The novelty and utility of the corrugated and perforated arms, I think, will be readily apparent.

The arms are let into the sockets between the curved sides, and butted against the hub, at f, and shouldered against the flange b, and fitted under it.

The under side of each socket has a square opening, and the arm is fitted into this opening, and on to the cross-bar d, in the form of a flush panel, H, and fastened by a screw or screws, n, through the bar d, and the side of the socket thus making the arm doubly secure.

In practice, the stand A is placed against the wall, beneath a projecting screw, m, and pushed upward, the sides 3 of the slot h passing each side of the screw. Another screw or projecting pin, 5, enters the slot or nick g and the plate A, and the rack or drier (having the arms or their sockets on the tapering spindles) is secured in position.

Having thus described my invention.

What I claim, and desire to secure by Letters Patent, is—

As an improvement on a clothes-drier, the stand A, spindles D, ears or plate C, sockets B, and arms E, all constructed, combined, and arranged in the manner and for the purpose specified.

EDWARD P. CLARK.
